(57) **CLAIM**

The ornamental designs for a refrigerator, as shown and described.

DESCRIPTION

FIG. 1 is a perspective view of a refrigerator according to a first embodiment of the present invention.

FIG. 2 is a front elevation view of the refrigerator of FIG. 1. FIG. 3 is a rear elevation view of the refrigerator of FIG. 1. FIG. 4 is a right side elevation view of the refrigerator of FIG. 1.

FIG. 5 is a left side elevation view of the refrigerator of FIG. 1.

FIG. 6 is a top plan view of the refrigerator of FIG. 1.

FIG. 7 is a bottom plan view of the refrigerator of FIG. 1.

FIG. 8 is a perspective view of the refrigerator of FIG. 1 with the doors thereof in an open position.

FIG. 9 is a perspective view of a refrigerator according to a second embodiment of the present invention.

FIG. 10 is a front elevation view of the refrigerator of FIG. 9.

FIG. 11 is a rear elevation view of the refrigerator of FIG. 9.

FIG. 12 is a right side elevation view of the refrigerator of FIG. 9.

FIG. 13 is a left side elevation view of the refrigerator of FIG. 9.

FIG. 14 is a top plan view of the refrigerator of FIG. 9.

FIG. 15 is a bottom plan view of the refrigerator of FIG. 9; and,

FIG. 16 is a perspective view of the refrigerator of FIG. 9 with the doors thereof in an open position.

The broken lines illustrate portions of the refrigerator and are environmental and form no part of the claimed design.

1 Claim, 16 Drawing Sheets
